(57) **CLAIM**

The ornamental design for a trailer hitch cover, as shown and described.

DESCRIPTION

FIG. 1 is a left side elevational view of a new design for a trailer hitch cover according to the present invention; the opposite side view being a mirror image thereof;

FIG. 2 is a top plan view thereof;

FIG. 3 is a bottom plan view thereof; the portions of FIGS. 1-3 that are broken lines are for the purpose of environment only and form no part of the claimed design;

FIG. 4 is a front elevational view thereof; and,

FIG. 5 is a rear elevational view thereof.
